UNITED STATES PATENT OFFICE.

HAROLD E. LUBKER, OF GRAND JUNCTION, COLORADO.

FISH-TAPE PULLER.

Application filed July 12, 1922. Serial No. 574,404.

To all whom it may concern:

Be it known that I, HAROLD E. LUBKER, a citizen of the United States, residing at Grand Junction, in the county of Mesa and 5 State of Colorado, have invented certain new and useful Improvements in a Fish-Tape Puller, of which the following is a specification.

My invention relates to tools of the type 10 adapted for use by electricians for pulling fish tape connected with electric work through conduits and pipes.

The primary object of the invention is to provide an efficient tool adapted for such 15 uses, constructed in a novel manner and so formed as to provide an efficient gripping surface for the fish tape, while at the same time allowing a direct pull without any danger of cutting or injuring the tape.

Another object of the invention is to provide a tool of this character comprising 20 pivoted jaws and handles constructed substantially along the lines of a nut cracker.

A further object of the invention is to 25 provide in a tool of this character guide means associated with the gripping jaws, for holding the tape in position and further provided with means for preventing any spreading of the jaws when in use.

With these and such other objects in view 30 as will be apparent from the description, the invention resides in the novel combination, construction and arrangement of parts hereinafter described and claimed, and 35 illustrated in the accompanying drawings, in which—

Figure 1 is a side elevation of the tool in gripping position;

Figure 2, a top plan view thereof;

40 Figure 3, a bottom plan view;

Figure 4, an enlarged detail elevation of the jaws in gripping position;

Figure 5, a detail elevation of the jaws in extended position;

45 Figure 6, a perspective illustrating one of the gripping jaws and handle; and

Figure 7, a detail section on the line 7—7 of Figure 4.

The tool comprises handles 1 and 2 provided 50 at their ends with sockets in which are received shanks 3 and 4, carrying lateral heads 5 and 6, provided with slightly rounded gripping jaws 7 and 8, one jaw 8 being slightly serrated to provide a more efficient gripping surface. Shanks 3 and 4 are

riveted or otherwise suitably secured in the handles 1 and 2 and the heads comprising the jaw members are pivoted at their outer ends to a U-bolt 9, the arms 10 and 11 of which extend through the heads and are threaded at their outer ends to receive suitable fastening means hereinafter described. At one side of the jaws the U-bolt 9 is provided with a plate 12 received over the arms of the bolt and on the opposite side 60 of the jaws is a plate 13 similarly disposed whereby any spreading of the jaws or lateral displacement is positively prevented. The plate 13 is loosely pivoted on the arm 11 of the tool and is provided adjacent the arm 10 with a recess 14 adapted to engage over the arm 10 when the plate is swung on the arm 11 as a pivot. The plate 13 is further provided with a stud 15 adapted to be engaged by a thumb screw 16 threaded 65 over the arm 10 to prevent the plate from becoming dislodged when in assembled position. A nut 17 threaded over the arm 11 serves to secure the plate 13 in position and both thumb nut 16 and nut 17 when tightened will draw the U-bolt, thereby effectually clamping the parts in assembled 70 position while at the same time permitting of a free pivotal movement between the jaws and the U-bolt.

The lower portion of one of the jaws is provided with lateral extensions 18 adapted to extend over and engage the opposite jaw in guiding relation whereby when the tool is clamped on the fish tape the same 75 will be received between the gripping jaws and held therein by means of the guides 80 18, as described.

In operation, the handles are extended until the tool assumes the position as illustrated in Figure 5; whereupon the fish tape previously attached to an electric wire adapted to be drawn through a conduit is passed between the gripping surface of the jaws and between the pivots on the U-bolt, 90 being guided and held therebetween by means of the plates 12 and 13. The handles are then swung outwardly and brought towards each other to bring the gripping 95 jaws into engagement with the fish tape on which the guide members 18 will act, as hereinbefore described, and by reason of the slightly curved formation of the jaws the positive and direct grip is secured on the 100 tape and the handles will assume the posi- 105 tion shown in Figure 1. The jaws are then 110

tion as illustrated in Figures 1, 2 and 3, permitting an efficient pull being exerted on the tape by reason of the fact that both hands of the operator may be employed.

- 5 When it is desired to disassemble the tool, the thumb nut 16 may be loosened from engagement with the stud 15 whereupon the plate 13 is swung on its pivot from its engagement with the U-bolt arm 10, after 10 which the nuts may be loosened to permit the U-bolt being withdrawn through the pivotal connection with the jaws.

While I have illustrated and described certain details which enter into the construction and operation of this invention, I desire it to be understood that I do not intend to limit myself to these, but that such may be used as will fall within the scope of the invention as claimed.

20 I claim:

1. A tool of the character described comprising a pair of handles, jaws carried by said handles, pivotal connection between the outer ends of said jaws, said jaws being adapted to receive an article to be gripped therebetween, and means associated with said pivotal connection for retaining said jaws against lateral displacement.

2. In a tool of the character described, a 30 pair of handles, gripping jaws carried by said handles and disposed in opposed relation, a U-bolt extending through the outer ends of said jaws to form a pivotal connection therebetween, a plate carried by said bolt at one side of said jaws, a plate carried by said U-bolt at the opposite side of said jaws and disposed in pivotal connection with

one of said jaws, and means for retaining said U-bolt and plates in assembled position.

3. In a tool of the character described, a 40 pair of handles, shanks disposed in said handles, laterally extending jaws integral with said shanks, said jaws being disposed in opposed relation and provided with slightly rounded gripping surfaces, a U-bolt 45 passed between the outer ends of said jaws whereby said jaws are connected in pivotal relation, a plate carried by the arms of said U-bolt at one side of said jaws, a plate carried by the arms of said U-bolt on the opposite 50 side of said jaws, and pivotally connected to one of the arms of said U-bolt, said last named plate being provided with a recess adapted to engage over the opposite arm of said U-bolt, nuts threaded on the free ends of 55 the U-bolt arms for clamping said bolt, arms and plates in assembled position, and work guiding members carried by one of said jaws and adapted to engage over the other of said jaws when the tool is in operative position.

4. In a tool of the character described, the combination with handles carrying opposed jaw members, of a U-bolt passed between said jaw members to provide a pivotal connection therebetween, work guiding 65 members carried by one of said jaws and adapted to engage over the other of said jaws, and plates carried by said U-bolt at opposite sides of the jaws and co-acting with said work guiding members to receive 70 and maintain the work passed between the jaws when the tool is in operative position.

In testimony whereof I affix my signature,
HAROLD E. LUBKER.
